UNITED STATES PATENT OFFICE.

EARL THOMPSON, OF NEW YORK, N. Y.

CHAIR.

1,375,868.

Specification of Letters Patent. Patented Apr. 26, 1921.

Application filed December 20, 1918. Serial No. 287,576.

To all whom it may concern:

Be it known that I, EARL THOMPSON, a citizen of the United States, residing at the city of New York, in the county of New York and State of New York, have invented certain new and useful Improvements in Chairs, of which the following is a specification.

My invention relates to improvements in chairs, and is particularly adapted for use in school chairs and seats adapted to orthopedic treatment and other chairs which are intended to be used continuously for any considerable period of time. In chairs of this character, it is desirable that the back of the occupant be supported in such manner as to relieve the muscles from undue strain and stretching forces and that there be provided adequate support for the lower back to maintain the lumbar curve and adjustable as may be required for each particular case, to accommodate the varying anatomical curves, variation of structure and bulk of clothes and no fixed curve can be devised to give proper support to all individuals. There must be direct support applied where it is most needed to prevent flexed and twisted positions and each chair should be fitted to a individual user and also adjustable as to the height of the seat so that the legs of the occupant of the chair may rest on the floor in a natural position. It is also important that the back of the chair should be vertical and not be inclined, as this construction tends to cause the user to assume a wrong position and to bring the upper spine, chest and neck forward in an unnatural posture. The upper back of the chair should not extend above the level of the shoulders of the user, but preferably to about that point when seated in a natural position. The chair back should be so constructed as to support the back and spine of the occupant in the natural position and maintain the torso, neck and head when seated in the position which should be assumed when standing erect. Neglect or failure in this respect tends to produce curvature of the spine, scoliosis, kymosis and other deformities. The object of my invention is to overcome the conditions which exist in the chairs now in use and to provide a chair which will produce the above mentioned desired results and will prevent and correct spinal curvature and deformity.

I accomplish this object by the device

illustrated in the accompanying drawing, in which Figure 1 is an elevation of my improved chair; Fig. 2 is a section on the line 2—2 in Fig. 1; Fig. 3 is a detail of the support for the lower back, with parts broken away, and Fig. 4 is a section on the line 4—4 in Fig. 1. Similar characters refer to similar parts throughout the several views.

Referring to the drawings, 1 is a chair having a back formed of two uprights 2 which extend to about the level of the shoulders of the occupant of the chair and carry at their upper ends a cross piece 3 pivoted between the uprights 2 on pins 4 which are preferably secured in the cross piece 3 by means of glue or the like and are each provided with a head 5 which turns freely in the upright 4 and are prevented from being withdrawn from the upright 4 by means of collars 6 therein whereby the cross piece 3 is adapted to swing on the pivots 4 to adjust itself to the correct chest position and upper back of the occupant of the chair and is limited in its movement by pins 7 inserted in the uprights 2 or in other suitable manner. Between the uprights 2 and above the seat of the chair, I provide a lumbar rest 8 which is preferably convex in the direction of the front of the chair and is adjustable vertically. For the purpose of vertical adjustment, I prefer to provide in the inner face of the uprights 2 a plate 9 having a plurality of perforations or seats 10 to receive the rounded heads 11 of the pins 12 which are mounted in the rest 8 and are normally pressed out into the seats 10 by springs 13 whereby the rest 8 may be adjusted vertically to accommodate the anatomical lumbar curve of the occupant, with space between the seat of the chair and the lumbar rest 8 to accommodate the buttocks and clothing. I also preferably provide on the upright 2 adjacent the ends of the rest 8 a guide bar 14 having a longitudinal slot 15 in which slides a set-screw 16 which may be turned down upon the bar 14 to bind the rest 8 in the desired position.

My device being thus assembled is designed to be adjusted to an individual user, for which purpose the lumbar rest 8 is positioned on the uprights 2 to provide proper support for the back of the occupant of the chair in the region of the lumbar vertebrae of said occupant and the cross bar 3 will, by reason of its flexible attachment to the

uprights 2, adjust itself to the proper and natural position for supporting the upper back and shoulders, whereby the back and chest of the occupant will be supported in 5 such manner as to relieve the muscles and vertebræ from undue strain and stretching forces, and direct support will be supplied where it is most needed to prevent a flexed and twisted position in the occupant.

10 I also provide on the base 1' of the legs of the chair 1 an extension screw 1² whereby the height of the chair may be adjusted to the occupant.

I have shown the back applied to a chair 15 seat of the usual construction but I do not intend to so limit my invention as it is obvious that it may be applied to chairs of any desired form and is particularly adapted for use in connection with school 20 chairs, orthopedic chairs and the like.

Having thus described my invention, what I claim is—

1. In a chair, a back, a lumbar rest thereon, a plurality of spring actuated pins 25 seated in said rest and adapted to detachably engage seats in the back, substantially shown and described.

2. In a chair the combination of a back having a plurality of uprights, seats in said 30 uprights, a lumbar rest in the back and

having a plurality of spring actuated pins seated thereon and adapted to detachably engage the seats in the uprights, a plate on the back adjacent said lumbar rest and having a longitudinal groove, a set screw 35 in said groove and engaging the rest whereby the rest may be locked in a fixed position.

3. In a chair, the combination of a back having a plurality of uprights, a cross piece pivoted between the uprights at approximately the height of the shoulders of the occupant and adapted to swing to adjust itself to the normal chest position of the occupant and means for limiting the swing 45 of the cross piece, and a lumbar rest positioned in the back below the cross piece.

4. In a chair the combination of a back, a cross piece pivoted thereon at approximately the height of the shoulders of the occupant and adapted to swing freely to 50 adjust itself to the normal chest position of the occupant, means for limiting the swing of the cross piece, a lumbar rest positioned on the back below the cross piece, means for adjustably positioning the lumbar rest 55 and means for adjusting the height of the chair substantially as shown and described.

In testimony whereof I affix my signature.

EARL THOMPSON.
